UNITED STATES PATENT OFFICE.

CHARLES H. BURTON, OF WASHINGTON, DISTRICT OF COLUMBIA, ASSIGNOR TO UNITED STATES PNEUMATIC COMPANY, OF NEW YORK, N. Y., A CORPORATION OF MAINE.

PNEUMATIC CONVEYER.

1,234,281.

Specification of Letters Patent. Patented July 24, 1917.

Application filed March 16, 1912. Serial No. 684,198.

To all whom it may concern:

Be it known that I, CHARLES H. BURTON, a citizen of the United States, residing at Washington, in the District of Columbia, have invented certain new and useful Improvements in Pneumatic Conveyers, of which the following is a full, clear, and exact description, such as will enable others skilled in the art to which it appertains to make and use the same.

This invention relates to pneumatic conveyers, and with regard to certain more specific features thereof, to pneumatic systems adapted to convey a carrier containing mail, merchandise or the like from one place to another.

One of the objects of the present invention is to provide a simple and practical apparatus of the above character which will be efficient in operation. Another object is to provide a self-contained apparatus for the above-mentioned purpose which will be inexpensive to manufacture and install. A further object is to provide a pneumatic tube system which will be substantially automatic in its operation and capable of handling a maximum of traffic with a given amount of apparatus. A further object is to provide an apparatus such as above-mentioned having interchangeable parts which will be silent in its operation and adapted to prevent shocks tending to damage contents of the carrier in starting and stopping. Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of this invention,

Figure 1 shows a complete system ready for operation;

Fig. 2 is an enlarged front elevation of one terminal;

Fig. 3 is a plan view of the terminal shown in Fig. 2;

Fig. 4 is a detailed sectional view of the terminal with the parts in position to receive a carrier;

Fig. 5 is a similar view of the same terminal taken from the opposite side with the

parts in position to discharge the carrier to a receiving table;

Fig. 6 is a detailed sectional view of the valves controlling the position of the trap- 60 valves;

Fig. 7 is a similar view of the valves for changing the terminal from a despatching to a receiving terminal or vice versa;

Figs. 8 and 9 are detailed views partially 65 in section showing the position of the controlling pistons actuating the trap-valves by the valve mechanisms shown in Figs. 6 and 7 respectively;

Fig. 10 is a transverse sectional view taken 70 through the central part of the terminal shown in Figs. 2 and 3;

Fig. 11 is an enlarged view showing the 75 position of damper-valves of the blower mechanism; and

Fig. 12 is a detailed view of a check-valve.

Figs. 13 and 13^a are details.

Similar reference characters refer to similar parts throughout the different views of the drawings.

Referring now to these drawings in detail and more particularly to Fig. 1 which shows the complete apparatus, 1 denotes the conveyer tube connecting the two terminals A and B. This tube 1 may be of any desired size, but, in practice, it is preferably composed of standard sections of eighteen or twenty-four inch cast iron pipe free from internal burs or projections, although it is unnecessary to grind the same to a smooth 85 surface. The system may be of any desired length and is laid under ground a few feet below the surface.

As the device is capable of sending carriers in either direction at will, a single tube 95 is all that is required in connecting any two stations. Inasmuch as the carrier, which is of substantially the style shown in my prior Patent No. 847,234, issued March 12, 1907, does not necessarily fit the tube 100 accurately or in an air-tight manner as usually required in pneumatic systems, the tube may be curved where necessary, as, for instance, when rounding street corners, providing, of course, that the radius of the 105 curve is not too small. In practice the carrier will easily negotiate any curve having a radius greater than twenty-one feet.

The present system is preferably operated upon the vacuum or suction principle operating upon the front of the carrier to draw it through the tube, in contradistinction to

the compressed air method of blowing the carrier from one terminal to another. A source of motive power is shown in Fig. 1 at each terminal comprising blower mechanism which will hereinafter be referred to more in detail and denoted broadly by the reference characters C and D; the general operation being that in drawing a carrier from terminal A to terminal B, the blower D is operated, tending to exhaust the air from the tube connecting these two terminals in advance of the carrier. In sending the carrier in the opposite direction, the blower mechanism C is operated instead in a similar manner.

It is quite clear that the vacuum principle has advantages over the compressed air system inasmuch as there is less air resistance to the carrier in going from one station to the other, and the natural air pressure acting behind the carrier is used, thereby decreasing the running expenses of the system. In other words, the difference of pressure on the opposite ends of the carrier when operated by compressed air is several times the difference in pressure when actuated on a vacuum principle.

Each terminal comprises, in brief, a pair of rear and front trap-valves 2 and 3 respectively spaced apart sufficiently to permit the carrier to come to rest therebetween due to the air cushion formed when the front trap-valve 3 is in closed position. These trap-valves and the casings therefor are of the same size and shape, as shown more clearly in Figs. 4 and 5, and are of the cylindrical type provided with a central transverse opening adapted to register with the bore of the tube and being of sufficient size to close the tube in an air-tight manner, by means of the solid portions 4, when in the position of the valve 2, Fig. 5. Each trap-valve is provided at one side and on the outside of the valve casing with a crank arm 5 carrying at its end a stud or pin 6. These pins are adapted to be engaged by slotted cam members 7 and 8, and given a quarter turn successively to change the valves from one position to another. The cam members comprise two upwardly projecting fingers denoted by the numerals 7 and 8, and two shorter upwardly projecting fingers 9 and 10, respectively, providing a slot therebetween for accommodating the crank pin 6 as it swings downwardly and around to turn the trap-valve.

One of these cam members is mounted at each end of a single or continuous piston rod 11 passing through a cylinder 12. They are supported in their sliding movement by means of guide-bars 13 directly connected with the valve casing. It will be noted that as the piston rod 11 reciprocates to the left from the position shown in Fig. 2, it will first rotate the trap-valve 2 to a closed posi-

tion before the pin 6 is drawn out of the slot between the fingers 8 and 10, whereupon the finger 7 will coact with the pin 6 of the trap-valve 3 to swing the same downwardly and around to open position, as shown in Fig. 5.

The movement of the piston rod 11 through the cylinder 12 is controlled by a system of valves E located at the central portion of each terminal. A main supply pipe 14 is connected with any convenient source of compressed air. Leading from the pipe 14 in one direction is a branch pipe 15 which branches into pipes 16 and 17 leading to the opposite ends of the cylinder 12 (see Figs. 6 and 10). Each of the branch pipes 16 and 17 is provided with a three-way valve 18 and 19 respectively provided with actuating arms 20 and 21 connected by a link 22 whereby they operate simultaneously.

It will thus be seen that with the valves in the position shown in Fig. 6, the air will pass through the valve 18 and the pipe 16 to force a piston-head 23 in the cylinder 12 to the right, as shown in Fig. 8. When the valves are given a quarter turn, however, the air is shut off from the pipe 16 and is permitted to pass through the valve 19 and pipe 17 to act upon the opposite side of the piston and move the same to the left. The air behind the piston is permitted to escape through a vent 24 of the valve 18 or a vent 25 of the valve 19, according to the direction in which the piston is moving.

This mechanism is controlled automatically upon the arrival of a carrier at the terminal. As the carrier moves toward the right (Fig. 2) in the main portion of the tube, with the trap-valves 2 and 3 open and closed, respectively, it engages a trigger 26 projecting downwardly into the tube as shown in Fig. 10. This trigger is mounted upon a transverse rock shaft 27 having rigidly secured thereto near its outer end a crank arm 28 which in turn is pivotally connected with the link 22; thus as the trigger is swung upward under the action of the carrier, it will move the link 22 to the right, thus closing the valve 18 and opening the valve 19, which in turn moves the piston-head 23 from right to left to close the trap-valve 2 and after a brief interval open the trap-valve 3 as previously described.

This movement of the piston rod 11 from right to left actuates a valve 30 (see Fig. 2) in a pipe 31 connected with a compressed air storage tank 32 to admit air into the trap-chamber to force the carrier shown at Fig. 5, out through the trap-valve 3 to a receiving table 34. As the carrier leaves the tube it engages a depending trigger 35 positioned midway in the tube and forces the same upward from the position shown in Fig. 5 to that shown in Fig. 2. This trigger 35 is mounted on a rock shaft 36 hav-

ing connected at one end thereof a crank 37 to which is pivotally connected a link 38. The opposite end of this link is connected to a crank arm 39 on the valve 19, Fig. 6.

5 It will thus be seen that as the trigger swings upwardly from the position shown in Fig. 5, it will move the link 38 in the direction of the entrance of the tube, thus rotating the valves into the former or normal position shown in Fig. 6, causing the air from the pipe 14 to pass through the valve 18 to move the piston 23 to the right; thus opening the trap-valve 2 which was previously closed, and closing the trap-valve 3, leaving 10 the apparatus in position to receive a second carrier.

15 As the time for discharging a carrier to the receiving table after entering the trap-chamber requires but a few seconds, the carriers may be sent one after another at the 20 rate of eight or ten a minute.

25 When it is desired to send a carrier in the opposite direction or convert the receiving terminal to a sending terminal, all that is required is to actuate a hand-lever 40 pivotally mounted at the receiving end of the 30 tube. This lever has pivotally connected therewith near its upper end a link 41 which is connected with a crank arm 42 of a three-way valve 43 in a pipe 44 which is one branch of a pipe 45 connected with the same compressed air supply entrance 14 previously described. An opposite branch 46 of the pipe 45 is provided with a similar three-way valve 47 having a crank arm 48 pivotally connected by means of a link 49 with the crank arm 42, whereby these valves operate simultaneously to open one and close the other as shown in detail view, Figs. 7 35 and 9.

40 The pipes 44 and 46 are connected with the opposite ends of a cylinder 50 having a piston 51 and a piston rod 52. This piston rod is provided at its end with a bifurcated 45 cam member 53 (see Fig. 4) similar to the cam members 7 and 8 previously described, whereby the parts may be more easily interchanged and replaced, which is adapted to engage a pin 54 on a crank arm 55 on the 50 opposite side of the trap-valve 3 from the crank 5. As this latter crank arm, shown in elevation in Fig. 2 at the opposite side of the trap-valve is free to turn independently of the cam member 8, the reversing mechanism 55 may be actuated independently of the trap controlling mechanism; thus when the lever 40 is pulled over to the right the valves 43 and 47 will be actuated to admit air to the cylinder 50 to force the piston 51 to the left, 60 thus giving the trap-valve 3 a quarter turn to open position. The trap-valve 2 being already open will in this manner provide a free passage through the terminal whereby a carrier may be sent from the receiving table 65 34 into the tube.

It is, of course, to be understood that in sending a carrier in the opposite direction, that is, for example from B to A, it is necessary to stop the blower mechanism D previously used when receiving the carriers at 70 B, and start the blower mechanism C to exhaust the air from the connecting tube or materially reduce the air pressure therein.

75 The blower mechanism for operating this system comprises an ordinary fan blower 56 connected with the tube 1 by means of a pipe 57. The fan is operated by a motor 58, the speed of which may be regulated by a controller 59, thereby indirectly regulating the speed of the carrier. The exhaust from the fan is directed through a pipe 60 to a compressed air tank 32, which, as above described, is used for blowing a carrier from the tube after being stopped in the trap-chamber. The upper part of the pipe 57 (see Fig. 11) is open to the atmosphere at 80 61 and is provided with a damper or valve 62 through which the air may be drawn when the blower at the opposite end of the system is in operation; thereby lessening the draft at the open end of the tube near the receiving table and eliminating the chances of articles of merchandise or the like being drawn therethrough into the tube. The valve 62 is connected by means of a cord or chain 63 with a crank arm 64 on a rock shaft 65 supporting a vane 66 in the tube or pipe 57 adjacent the blower. It is thus seen that when the blower is started the vane 66 will be drawn upwardly into the position shown 85 in Fig. 11 due to the suction of the air which, through the connecting means above mentioned, closes the valve 62, thus insuring the exhaustion of the air from the tube 1 more rapidly.

90 In order to prevent accidents which might arise by inadvertently leaving both the front and rear trap-valves 2 and 3 open after despatching a carrier, there is provided automatically operated means for restoring the trap-valves to normal position; that is, the rear trap-valve 2 open and the front trap-valve 3 closed, so that if a carrier should be immediately returned it would be arrested in the trap-chambers above described. This 95 may be conveniently done by positioning in the T-connection 68, between the pipe 57 leading from the blower and the main body of the tube 1, a trigger 69 positioned in the path of travel of the carrier. This trigger, 100 like the trigger 26, is so connected with a rock shaft 70 supporting the same that it is permitted to swing free in one direction, yet rotate the rock shaft when moved in the opposite direction by the carrier. The lost 105 motion connection referred to is illustrated in Figs. 13 and 13^a as applied to the rock shaft 27 and the trigger 26. It will be understood that one of the collars illustrated 110 is fastened to the shaft and the collar 26^a 115 is fastened to the shaft and the collar 26^a 120 is fastened to the shaft and the collar 26^a 125 is fastened to the shaft and the collar 26^a 130

carrying the trigger 26 rotates thereupon a segment 26^b working in the cut-out portion of the other collar. Of course any other form of lost motion otherwise could be employed, and the same arrangement is applied to the trigger 69. This rock shaft 70 is provided with a crank arm 71 and a link 72 connected with the link 49 (Fig. 7). It will thus be noted that as the carrier passes out through the tube it will engage the trigger 69 and swing the same upwardly to move a connecting rod 72 to the left; that is, to carry the parts into the position shown in Fig. 7, it being remembered, of course, that when sending the carrier, the valve 47 was closed and the valve 43 opened, thereby opening the front trap-valve 3. If a second carrier is to be despatched immediately afterward, it is again necessary to pull the lever 40 forwardly in order to open the trap-valve 3. This mechanism is otherwise entirely automatic in returning the parts to normal position.

Although it is thought from the above description that the operation of the device may be clearly understood, it will, however, be set forth in brief as follows:—

Assuming that a carrier is to be sent from B to A, with the apparatus in the position shown in Fig. 1, the blower C is started to exhaust the air from the tube 1 which will draw in a carrier through the open trap-valves 2 and 3 of the terminal B from the receiving platform 34; the carrier passes through the tube toward the terminal A and through the open trap-valve 2 at terminal A into the trap-chamber where its momentum is arrested by the compressing of the air against the closed valve 3. A vent 73 is preferably provided at the forward end of the trap-chamber having therein a check-valve 74, as shown in Fig. 12. Compression of the air by the carrier will close the check-valve which is normally open to permit the inlet of air when the system is operated in the opposite direction. Otherwise a partial vacuum would be formed, thereby decreasing the cushioning effect of the trap-chamber. As the carrier passes into the trap-chamber it engages the trigger 26 which actuates the valve mechanism E to open the trap-valve 3 and close the trap-valve 2 and also open the valve 30 to permit an inlet of compressed air through the pipe 31 to move the carrier 33 out upon the receiving platform 34. The carrier swings the trigger 35 upwardly which restores the valve mechanism E to its former position, thus opening the valve 2 and closing the valve 3 so that the device is ready for receiving another carrier. If, however, it is desired to send a carrier in the opposite direction, the blower mechanism C is stopped and the signal is given to the operator at the terminal B to start the blower mechanism D. The lever

40 is then pulled forward to actuate the valve shown in Fig. 7, which in turn affects the trap-valve 3 only. The carriers may then be introduced into the tube at the terminal A at regular intervals and the operation above set forth takes place at the terminal B.

It is, of course, to be understood from the previous description that before despatching a second carrier from any terminal it is necessary to pull the lever 40 forward to open the front trap-valve 3, as this valve is automatically closed after each carrier engages the trigger mechanism in the T-connection 68 after leaving the trap-chamber.

It is thus seen that this invention provides a simple and practical device comprising but a single connecting tube through which carriers may be sent in either direction, with a minimum amount of effort on the part of the operator, requiring no material changes in the apparatus. The fact that the system comprises but a single tube and is operated on the vacuum principle of course greatly diminishes the cost of construction and installation. It is therefore quite clear that the invention accomplishes, among others, all the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

1. In an apparatus of the character described, in combination, a pair of terminals spaced apart, a single tube connecting said terminals, means for reducing the air pressure in the tube for drawing a carrier therethrough, means associated with each of said terminals for changing the same from receiving to despatching terminal, at will, and means adapted to be actuated automatically by the carrier passing through a terminal in either direction for restoring the terminal to receiving position.

2. In a pneumatic conveyer, a pair of terminals, a tube connecting them, means at each terminal for converting it at will from a receiving to a despatching terminal, means at each terminal for exhausting the air from

the tube and thus acting upon a carrier at one terminal by the exhausting means at the other; a delivery station, an air cushion chamber for arresting the motion of the carrier, and means acting after the carrier has been arrested for moving it from the cushion chamber to the delivery table.

3. In a pneumatic conveyer, terminals spaced apart, a tube connecting them, means 10 for converting a selected terminal from a receiving to a despatching station, means at each terminal acting in alternation to exhaust the air from the tube and thus acting upon a carrier at one terminal by the exhausting means at the other; a delivery station, an air cushion chamber for arresting the carrier, and means for delivering the exhaust behind the carrier to bring it from the air cushion chamber to the delivery station.
- 15 4. In an apparatus of the character described, in combination, a pair of terminals spaced apart, a single tube connecting said terminals, means associated with each of said terminals for changing the same from 20 a receiving to a despatching terminal at will, means operative at one end for acting on a carrier on the opposite end of the tube, means for arresting the passage of a carrier through the tube prior to its final delivery 25 at the end of the system, and means adapted to direct a current of air to a point behind the carrier after it had been arrested for forcing the carrier out of the terminal.
- 30 5. In a pneumatic conveyer, in combination, a terminal comprising means for reducing the air pressure in advance of a carrier as it passes through the tube, a pair of trap valves spaced apart near the end of said tube and forming a trap chamber therebetween adapted to arrest the movement of the carrier, a delivery station, and means for increasing the air pressure behind the carrier after the same has been arrested to force the carrier from the tube to the delivery station.
- 35 45 6. In an apparatus of the character described, in combination, a tube through which a carrier is adapted to pass, means adapted to reduce the air pressure in advance of the carrier to draw the carrier 40 through said tube, a trap chamber adapted to arrest the movement of the carrier, a delivery station adjacent said trap chamber, and means adapted to conduct the air exhausted from said tube to said trap chamber to force the carrier out of said trap chamber to said delivery station after its 45 movement is arrested.
- 50 7. A terminal for a system of the character described, comprising in combination, a pair of trap valves forming a trap chamber therebetween, a cylinder positioned between said valves, a single piston rod adapted to be actuated by said cylinder for controlling the position of the valves, connections between the piston rod and the valves

for actuating the valves, means for admitting compressed air to one side or the other of the piston for opening one of the trap valves and closing the other, said last-mentioned means being actuated by the passage 70 of a carrier into the trap chamber, and means adapted to open one of said valves whereby said terminal may be converted to a despatching terminal.

8. A terminal for a system of the character described, comprising in combination, a trap chamber formed by a pair of front and rear trap valves, pneumatic means adapted to be actuated by the entrance of a carrier into said trap chamber for actuating the valves to permit the carrier to leave said chamber, means actuated by said first-mentioned means for admitting air pressure behind said carrier for forcing the same out of the chamber, and means adapted to open one of said valves whereby said terminal may be converted to a despatching terminal.

9. A terminal for a system of the character described, in combination, a trap chamber formed by a pair of front and rear trap valves, pneumatic means adapted to be actuated by the entrance of a carrier into said trap chamber for actuating the valves to permit the carrier to leave said chamber, positively operated means actuated by said first-mentioned means for admitting air pressure behind said carrier for forcing the same out of the chamber, and positively 95 acting automatic means for restoring the 100 valves to receiving position after the carrier leaves the chamber.

10. A terminal for a system of the character described, in combination, a trap chamber formed by front and rear trap valves, the first of which is normally closed and second normally open, means adapted to be positively actuated by a carrier entering said chamber for reversing the position of the valves to permit the exit of the carrier, and means actuated by said first-mentioned means for permitting compressed air to enter the chamber behind the carrier in order to force the same out of the chamber.

11. A terminal for a system of the character described, in combination, a trap chamber formed by front and rear trap valves adapted to cushion and arrest the movement of a carrier on entering the chamber, means adapted to reverse the position of the trap valves, a lever in the path of travel of the carrier between the trap valves for actuating said means, a source of compressed air connected with the rear of the chamber, and a valve adapted to be 120 opened by said first-mentioned means for admitting compressed air to said chamber to blow out the carrier after the trap valve is opened.

12. A terminal for a system of the character

ter described, in combination, a tube, exhausting means connected therewith, a trap chamber formed by front and rear trap valves, a crank arm for each of said valves, 5 a cylinder and piston positioned therebetween, connections between the piston rod and said crank arms, a system of valves adapted to be opened or closed to move said piston back and forth, means actuated by a carrier on entering said trap chamber 10 for closing the rear trap valve and opening the front trap valve, whereby the carrier may be discharged from the tube, a source of compressed air connected with the rear 15 of said chamber from said exhausting means, a valve, and means connecting said piston with said valve for admitting air to the chamber after the front trap valve has been opened, whereby the carrier is blown 20 out of said chamber.

13. In a receiving or despatching terminal for an apparatus of the character described, in combination, a tube having a pair of valves spaced apart for opening or closing 25 the passage of a carrier through the tube, automatic means for positioning said valves for receiving a carrier after each operation of receiving or despatching, and means for positioning said valves whereby the carrier 30 may be despatched.

14. In a receiving or despatching terminal for an apparatus of the character described, in combination, a tube having a pair of valves spaced apart for opening or closing 35 the passage of a carrier through the tube, means for positioning said valves for receiving or despatching a carrier, said means acting automatically to return the parts to normal position after the carrier has been 40 despatched or received.

15. In a receiving or despatching terminal for an apparatus of the character described, in combination, a tube having a pair of valves spaced apart for opening or closing 45 the passage of a carrier through the tube, automatic means for positioning said valves for receiving a carrier, means for positioning said valves whereby the carrier may be despatched, and automatic means 50 for returning the parts to normal position after the carrier has been despatched, said last-mentioned means comprising a member projecting in the path of travel of the carrier, and valve mechanism adapted to be 55 actuated thereby for restoring the front trap valve to closed position.

16. In a receiving or despatching terminal for an apparatus of the character described, in combination, a tube having a 60 pair of trap valves spaced apart at one end thereof forming a trap chamber therebetween, the rear valve being normally open and the front valve normally closed to form an air cushion for arriving carriers, manually operated means for opening the front 65

trap valve only whereby a carrier may be despatched in the opposite direction, and automatic means actuated by the carrier after passing through the rear trap valve for closing the front trap valve whereby the 70 device is in position to receive a carrier.

17. In a receiving or despatching terminal for an apparatus of the character described, in combination, a tube having a pair of trap valves spaced apart at one end 75 thereof forming a trap chamber therebetween, the rear valve being normally open and the front valve normally closed to form an air cushion for arriving carriers, manually operated means for opening the front 80 trap valve whereby a carrier may be despatched in the opposite direction, and automatic means actuated by the carrier after passing through the rear trap valve for closing the front trap valve whereby the device 85 is in position to receive a carrier, said means including a cylinder and a piston actuated thereby and a connection between the piston and the crank arm of the front valve.

18. In a receiving or despatching terminal for an apparatus of the character described, in combination, a tube, front and rear trap valves forming a trap chamber 90 therebetween, the rear valve being normally open and the front valve normally closed, means between said valves within said trap chamber adapted to be actuated by a carrier for closing the rear valve and opening the front valve whereby the carrier may be 95 discharged to a receiving table, and means actuated by the carrier on passing out of the tube for restoring the trap valves to normal position.

19. In a receiving or despatching terminal for an apparatus of the character described, in combination, a tube, front and rear trap valves forming a trap chamber 100 therebetween, the rear valve being normally open and the front valve normally closed, means between said valves within said trap chamber adapted to be actuated by a carrier for closing the rear valve and opening the front valve whereby the carrier may be discharged to a receiving table, means actuated 105 by the carrier on passing out of the tube for restoring the trap valves to normal position, and means for actuating the front trap valve independently of the rear trap valve whereby the device may be converted 110 into a despatching terminal, at will.

20. In a receiving or despatching terminal for an apparatus of the character described, in combination, a tube, front and rear trap valves forming a trap chamber 115 therebetween, the rear valve being normally open and the front valve normally closed, means between said valves within said trap chamber adapted to be actuated by a carrier for closing the rear valve and opening the 120 front valve.

- front valve whereby the carrier may be discharged to a receiving table, means actuated by the carrier on passing out of the tube for restoring the trap valves to normal position, and means for actuating the front trap valve independently of the rear trap valve whereby the device may be converted into a despatching terminal at will, said last-mentioned means comprising a cylinder with a piston therein and a loose connection between said piston and the crank of said front trap valve for permitting independent action thereof.
21. In a system of the character described, in combination, a single tube having a terminal at each end thereof, blower mechanism at each terminal adapted to create a partial vacuum in the tube to advance the carrier, a trap chamber in each terminal for arresting the carrier, means for releasing the carrier, a delivery station, and a connection between the blower mechanism and trap chamber for directing the exhaust from the blower mechanism to the chamber at a point behind the carrier for blowing the same out of the tube delivery station when released.
22. In a system of the character described, in combination, a tube, a terminal, a station at each end thereof, blower mechanism at each terminal adapted to be operated to draw a carrier therethrough, a trap chamber for arresting the carrier on its arrival at the terminal, valve mechanism adapted to be actuated to permit the discharge of the carrier from the trap chamber, a delivery station and a connection between the exhaust of the blower and the trap chamber for forcing the carrier out of the chamber to the delivery station when released by the actuation of the valve mechanism.
23. In a system of the character described, in combination, a tube, a terminal, a station at each end thereof, a blower mechanism at each terminal adapted to draw a carrier therethrough, a trap chamber for arresting the carrier on its arrival at the terminal, valve mechanism adapted to be actuated to permit the discharge of the carrier from the trap chamber, a connection between the exhaust of the blower and the trap chamber for forcing the carrier out of the chamber when released by the actuation of the valve mechanism, and a valve in said connection adapted to be opened by the operation of the valves of the trap chamber.
24. In an apparatus of the character described, in combination, a tube, a terminal, a station at each end thereof, blower mechanism connected with each terminal for reducing the air pressure in the tube, a connection between the blower and the tube, and a valve in said connection controlling an opening to the atmosphere adapted to close automatically with the starting of the blower.
25. In an apparatus of the character described, in combination, a tube having a terminal at each end thereof, a blower for reducing the air pressure in the tube, a connection between the blower and the tube, a damper in said connection adjacent an opening leading to the atmosphere, and means in said connection adapted to be actuated on starting the blower for closing the opening by said damper whereby the air is drawn out of said tube.
26. In an apparatus of the character described, in combination, a terminal for a pneumatic tube operated by vacuum, two trap valves forming an air cushion chamber therebetween, a single piston rod operating the trap valves from a single cylinder, a delivery station, an inlet valve, and means for opening said inlet valve for the purpose of admitting compressed air to eject the carrier to the delivery station after it has been received in the air cushion chamber.
27. In an apparatus of the character described, in combination, a tube, means adapted to reduce the air pressure in said tube, two trap valves forming an air cushion chamber therebetween in said tube, and a separate inlet valve in said chamber to prevent the exhaustion of air by said pressure reducing means.
28. In an apparatus of the character described, in combination, a tube, and an exhauster connected with said tube, two trap valves therein forming an air cushion chamber therebetween, and a separate inlet valve in said chamber to prevent the exhaustion of air, said inlet valve adapted to close automatically by compression of air caused by the injection of the carrier into the air cushion.
29. In a terminal for a system of the character described adapted to receive a carrier and to have a carrier despatched therefrom, in combination, means for placing said terminal in despatching condition, means for placing said terminal in receiving condition, and means coöperating with said last-mentioned means adapted to automatically place said terminal in receiving condition upon the departure of a despatched carrier from said terminal.

In testimony whereof I affix my signature, in the presence of two witnesses.

CHARLES H. BURTON.
